HARROW SNUBBER

Frederick C. Warne, Mansfield, Ohio, assignor to
 Farm Tools, Inc., Mansfield, Ohio, a corpora-
 tion

Application January 21, 1938, Serial No. 186,115

20 Claims. (Cl. 55—81)

This invention relates to improvements in disc harrows and particularly to snubbing means to resist the tendency to upward thrust of the inner ends of two oppositely extending and mutually reacting disc gangs. The invention is useful in connection with any disc gang of this type but is of particular importance in connection with wide disc harrows of the sectionalized type as shown for instance in my United States Letters Patent No. 2,098,116 and my pending application for patent Serial No. 106,517. In harrows of this type the weight of each section is such that there develops a very marked tendency to upward thrust of the inner ends of the gangs. Efforts have been made to overcome this in prior disc harrows by various snubbing means but insofar as my knowledge goes all of the devices heretofore attempted have functioned upon a principle which tended to bring the inner adjacent ends of the gangs closer together, thus exerting too great an end thrust and binding effect against the bumper washers and bearings.

It is, therefore, the main object of the present invention to provide a snubbing device which will very effectively eliminate the tendency of the inner arms of the gangs to rise but which will at the same time maintain the normal end thrust between the bumper washers and avoid binding at that point.

A further object of the invention is to so design and construct the snubbing device that it will not interfere in any way with the necessary angling of the harrow sections and still allow the snubbing device to function efficiently.

A further object is to provide a device for the purpose which may be easily attached to any harrow of this type and necessitating few if any changes to the harrow as originally constructed.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Figure 1 is a top plan view of the snubber as applied to the harrow, showing the gangs in parallel position.

Figure 2 is a view similar to Fig. 1 showing the gangs in angled position.

Figure 3 is a longitudinal or side view of the same partly in section.

Figure 4 is a view similar to Fig. 3 but illustrating a modified form of the invention.

Referring now more particularly to the characters of reference on the drawings, the harrow proper comprises separate harrow gang frames 1 having cross angle members 2 at their adjacent ends, such ends of the gang being separated some distance from each other as usual. The discs 3 are mounted in connection with each frame as usual, the adjacent endmost discs having contacting bumper washers 4 as is customary.

The main draft fork 5 of the harrow is separately pivoted in connection with the frames 1, 15 in the ordinary manner, the bumpers 4 being curved concentric with the pivots so that the frames can swivel relative to each other while maintaining the bumpers in engagement.

My improved snubber as applied to the above mentioned standard harrow construction, includes a rigid saddle extending between and slidably resting on the cross members 2 and comprising generally a pair of spaced angle bars 8. A pair of pivot pins 9, one adjacent each end of the bars 8, and a central pivot pin 10, effectively secure the spaced bars 8 together as a unit to form a rigid truss saddle.

Levers 11 project between the saddle bars 8 and are pivoted intermediate their ends on the pins 9.

A V-shaped rocking bracket 12 at its apex surrounds the pivot pin 10 for free rocking movement thereabout. The adjacent inner ends of the levers 11 are provided with yokes 13 mounted over the arms of the bracket 12 for free sliding movement thereon. The free ends of the arms 12 are threaded as at 14 to receive adjustment nuts 15 and interposed between each of these nuts and the corresponding yokes 13 are coil springs 16. As is obvious, the tension of the springs relative to the levers 11 may be adjusted by movement of the nuts 15 on their threads 14.

The outer end of each lever 11 is pivotally mounted at 17 on an angle iron 18 these angle irons being pivoted at 19 to the under sides of one of the side angle irons of each gang frame 1. The opposite ends of the angle irons 18 bear against the under side of the opposite side angles of the gangs 1 so that the angle irons 18 are free to have a swinging movement underneath the gang frames about the pivots 19, when the gangs are angled relative to each other.

From the foregoing description it will be apparent that the saddle 8, bracket 12, arms 11

and the angle irons 18 form a substantial truss like unit structure between the gang frames when the adjustment nuts 15 are set to put the springs 16 under substantial tension. Since the saddle 8 overlies and rests on the immediate adjacent ends of the gang frames and the levers 11 are pivoted at the ends of this saddle and to the gang frames at points outwardly of the points at which the saddle rests on the frames, these levers, when stopped at their inner ends against the springs 16, tend to exert a lifting action on the gang frames beyond the points at which the saddle 8 rests on the adjacent inner ends of the gangs. This tendency to a lifting action will therefore very definitely resist and overcome the tendency of the outer ends of the gangs to sag downwardly and impart a consequent upward thrust to the inner ends of the gangs. At the same time, the pivotal mounting of the bracket 12 and such resiliency as may be permitted to the springs 16 will allow a flexibility of movement to prevent undue strains being placed on the working parts. The degree of resilient flexibility desired may be quite easily controlled through the movement of the adjustment nuts 15. If considerable amount of flexibility is desired the nuts will be retracted towards the outer ends of the arms of the brackets 12. Less flexibility can be attained by a reverse action of the nuts which reverse action can be carried to the extreme by taking all the resiliency out of the springs leaving the assembly completely rigid against upward thrust of the ends of the gangs.

It will be obvious that there is no resistance to the inner ends of the levers moving in a downward direction so that when the outer end of the harrow strikes obstructions or uneven ground which tends to raise such outer ends, this action may be permitted without possibility of undue strains being placed on the working parts.

The straight line distance between the pivot pins 9 of the snubber levers is obviously greater than the corresponding distance between the draft fork pivots so that when the harrow frames are angled about said latter pivots the normal distance between the pivots 17 of course tends to decrease. This is compensated for by the swinging movement afforded the angle irons 18 on their pivots 19. When the frames are thus positioned at an angle to each other the cross members 2 likewise slide under the saddle 8 and the relative position of the latter is altered as indicated in Fig. 2, but this does not effect the snubbing action of the device as will be evident.

In Fig. 4 there is shown a modified form of support and adjustment of the inner ends of the snubber levers. In this structure the rocking V-shaped bracket 12 and its associated parts are not used. Instead there is provided a yoke 12a secured to and overhanging the saddle 8a and a pair of set screws 15a project through this yoke and the inner adjacent ends of the levers 11a project under and bear against these set screws. The set screws act as the stops for the inner ends of the levers 11a by which the lever action is controlled to tend to exert the desired lifting action on the gang frames beyond the point at which the saddle rests on the ends of the gang frames and thus prevent the tendency to upward thrust of the inner ends of the gang frames. The desired position and action of the parts may be controlled by the adjustment of these set screws 15a. The functioning of this modified structure is the same as that of the preferred structure except that it is not provided

with the flexible cushioning effect afforded by the use of the springs 16.

It will also be quite obvious that while this truss structure very definitely functions to attain the above objectives, there is no tendency at any time during its functioning for the adjacent ends of the gang frames to be moved or pulled toward each other but they will be definitely held substantially in normal spaced relation. This is an important feature of my invention and presents a distinct advantage over previous snubbers in that there is no additional end thrust exerted against the bumper washers 4 and the bearings of the discs.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. In a disc harrow the combination with two oppositely extending mutually reacting disc gangs with draft means connected therewith of a truss saddle over-reaching from one gang frame to the other, levers pivoted to the saddle and the gang ends for swinging movement in a vertical plane, and means to resist upward movement of the adjacent ends of the levers. 35

2. In a disc harrow the combination with two oppositely extending mutually reacting disc gangs with draft means connected therewith of a truss saddle over-reaching from one gang frame to the other, levers pivoted to the saddle and the gang ends for swinging movement in a vertical plane, means to resist upward movement of the adjacent ends of the levers, such means including a V-shaped bracket mounted on the saddle for rocking movement about its apex, the levers having yokes slidable over the bracket arms, and means to limit such movement in an upward direction. 40

3. In a disc harrow the combination with two oppositely extending mutually reacting disc gangs with draft means connected therewith of a truss saddle over-reaching from one gang frame to the other, levers pivoted to the saddle and the gang ends for swinging movement in a vertical plane, means to resist upward movement of the adjacent ends of the levers, such means including a V-shaped bracket mounted on the saddle for rocking movement about its apex, the levers having yokes slidable over the bracket arms, and means to limit such movement in an upward direction, such latter means comprising stops on the ends of the bracket arms and yielding elements interposed between the stops and the lever ends. 55

4. In a disc harrow the combination with two oppositely extending mutually reacting disc gangs with draft means connected therewith of a truss saddle over-reaching from one gang frame to the other, levers pivoted to the saddle and the gang ends for swinging movement in a vertical plane, means to resist upward movement of the adjacent ends of the levers, such means including a V-shaped bracket mounted on the saddle for rocking movement about its apex, the levers having yokes slidable over the bracket arms, and 70

means to limit such movement in an upward direction, such latter means comprising adjustable stops on the ends of the bracket arms and yielding elements interposed between the stops and 5 the lever ends.

5. In a disc harrow the combination with two oppositely extending mutually reacting disc gangs with draft means connected therewith of a truss saddle over-reaching from one gang frame to 10 the other, levers pivoted to the saddle and the gang ends for swinging movement in a vertical plane, means to resist upward movement of the adjacent ends of the levers, such means including a V-shaped bracket mounted on the saddle for 15 rocking movement about its apex, the levers having yokes slideable over the bracket arms, and means to limit such movement in an upward direction, such latter means comprising threaded ends on the bracket arms, nuts mounted for 20 movement on the threads and springs interposed between the nuts and lever ends.

6. In a disc harrow the combination with two oppositely extending mutually reacting disc gangs with draft means connected therewith of a truss 25 saddle over-reaching from one gang frame to the other, levers pivoted to the saddle and the gang ends for swinging movement in a vertical plane, means to resist upward movement of the adjacent ends of the levers, and means to compensate for the tendency to relatively change 30 the position between the gang ends and levers when the gangs are angled relative to each other.

7. In a disc harrow the combination with two oppositely extending mutually reacting disc gangs 35 with draft means connected therewith of a truss saddle over-reaching from one gang frame to the other, levers pivoted to the saddle and the gang ends for swinging movement in a vertical plane, means to resist upward movement of the adjacent ends of the levers, and means to compensate for the tendency to relatively change the position between the gang ends and levers when the gangs are angled relative to each other, such 40 means including supports pivoted for swinging movement on adjacent gang ends, the outer ends 45 of the levers being pivoted to the supports.

8. In a disc harrow the combination with two oppositely extending mutually reacting disc gangs with draft means connected therewith of a truss 50 saddle over-reaching from one gang frame to the other, levers pivoted to the saddle and the gang ends for swinging movement in a vertical plane, means to resist upward movement of the adjacent ends of the levers, and supports pivoted 55 for swinging movement on adjacent gang ends, the outer ends of such levers being pivoted to such supports.

9. In a disc harrow the combination with two oppositely extending mutually reacting disc gangs 60 with draft means connected therewith of a truss saddle over-reaching from one gang frame to the other, levers pivoted to the saddle and the gang ends for swinging movement in a vertical plane, and means to resist upward movement of the adjacent ends of the levers, such means including 65 stops mounted on the saddle against which the adjacent ends of the levers impinge.

10. In a disc harrow the combination with two oppositely extending mutually reacting disc gangs 70 with draft means connected therewith of a truss saddle over-reaching from one gang frame to the other, levers pivoted to the saddle and the gang ends for swinging movement in a vertical plane, and means to resist upward movement of the adjacent ends of the levers, such means in- 75

cluding adjustable stops mounted on the saddle against which the adjacent ends of the levers impinge.

11. In a disc harrow the combination with two oppositely extending mutually reacting disc gangs 5 with draft means connected therewith of a truss saddle over-reaching from one gang frame to the other, and resting on the adjacent ends of the gang frames, and means between the saddle and the gang frames beyond the points at which 10 the saddle rests on such frames to resist upward thrust of the inner ends of the gangs.

12. In a disc harrow the combination with two oppositely extending mutually reacting disc gangs 15 with draft means connected therewith of a truss saddle over-reaching from one gang frame to the other and resting on the adjacent ends of the gang frames, levers pivoted on the saddle and projecting beyond the opposite ends thereof, and means securing the outer ends of the levers 20 to the gang frames beyond the point at which the saddle rests on such frames.

13. In a disc harrow the combination with two oppositely extending mutually reacting disc gangs 25 with draft means connected therewith of a truss saddle over-reaching from one gang frame to the other and resting on the adjacent ends of the gang frames, levers pivoted on the saddle and projecting beyond the opposite ends thereof, means securing the outer ends of the levers to 30 the gang frames beyond the point at which the saddle rests on such frames, and means between the levers and saddle to adjust the levers vertically relative to the saddle.

14. In a disc harrow the combination with two 35 oppositely extending mutually reacting disc gangs with draft means connected therewith of a truss saddle over-reaching from one gang frame to the other and resting on the adjacent ends of the gang frames, levers pivoted on the saddle 40 and projecting beyond the opposite ends thereof, means securing the outer ends of the levers to the gang frames beyond the point at which the saddle rests on such frames, and means between the levers and saddle to adjust the levers vertically 45 relative to the saddle, such means comprising vertically adjustable set screws carried by the saddle and engaging the inner ends of the levers to raise the outer ends of the levers with an advancing movement of the set screws. 50

15. In a disc harrow the combination with oppositely extending mutually reacting disc gangs which comprise gang frames, bumper washers on the adjacent ends of the gangs and draft means, of a truss saddle over-reaching from one gang 55 frame to the other and supported thereon, and embodying means to reduce end thrust between the bumper washers.

16. In a disc harrow the combination with oppositely extending mutually reacting disc gangs 60 which comprise gang frames, bumper washers on the adjacent ends of the gangs and draft means, of a snubber over-reaching from one gang frame to the other, and embodying means to reduce end thrust between the adjacent inner ends of 65 the gang frames and the bumper washers.

17. In a disc harrow, the combination with oppositely extending mutually reacting disc gangs which comprise gang frames and draft means applied thereto, of a truss structure extending 70 between and engaging the frames at a point on each frame adjacent its inner end; said structure embodying elements substantially rigid with each other and connected to the frames at points beyond said first named points and means to 75

exert a lifting action on the gang frames at the points of connection of the elements therewith.

18. In a disc harrow, the combination with oppositely extending mutually reacting disc gangs which comprise gang frames and draft means applied thereto, of a snubber structure over-reaching from one gang frame to the other and embodying means for exerting a lifting action on the gang frames at points spaced from their adjacent ends while at the same time exerting a lowering action on the frames at said ends.

19. In a disc harrow, the combination with oppositely extending mutually reacting disc gangs which comprise gang frames and draft means applied thereto, of a truss structure extending between and engaging the frames at a point on each frame adjacent its inner end; each frame being capable of rocking movement in a vertical

plane about said point; said structure embodying means to exert a lifting action on the frames at points beyond said rocking points in a direction away from the adjacent end of the gang frames.

20. In a disc harrow, the combination with oppositely extending mutually reacting disc gangs which comprise gang frames and draft means applied thereto of a truss structure connecting the gang frames and comprising a saddle extending between and resting and slidable on said frames at their adjacent ends and levers projecting in opposite directions from the saddle and held against unrestrained movement at their adjacent ends and means pivoting the levers at their outer ends on the frames beyond said adjacent ends thereof.

FREDERICK C. WARNE.
